UNITED STATES PATENT OFFICE

EDWARD HENRY RIDER, OF VICTORIA, BRITISH COLUMBIA, CANADA

COMBINATION CRUSHER AND SEPARATOR

Application filed February 20, 1928, Serial No. 255,845, and in Canada October 31, 1927.

This invention relates to a combination crusher and separator, its prime object has special reference to the preparation and rendering marketable of a certain natural product or deposit consisting chiefly of clam shell or portions thereof intermixed with pebbles, pieces of rock and the like. The purpose of the machine being to break or partially crush the larger shells only and to exclude or separate therefrom the pebbles or rock portions, which are then evacuated as refuse from the machine.

Although the machine is primarily designed for this purpose it will be obvious that by slight modifications which would not affect the general principles of construction involved that it could be utilized for a variety of other purposes without departure from the spirit of the invention nor exceeding the limitations of the claim.

The clam shell material above referred to, which exists in large deposits consists of practically pure lime, and provided that it can be rapidly and cheaply freed from the accompanying débris with which it is almost invariably found, forms a commercial commodity of great comparative value.

The means which I adopt in this invention for effecting the above named objects, namely the garnering of all the lime ingredients, and the reduction of the larger pieces to the commercial limit, whilst rejecting the pebbles and other débris, consists in its essentials of an inclined chute into the upper part of which the crude material is gradually and evenly delivered by an adapted conveyer or other suitable means. The inclination of the chute is fixed at such an angle that the material readily slides by gravitational effect according to the volume of the feed, and passing under a revolving circumferentially grooved roller is subjected to an adjustable pressure sufficient to break the larger shell portions but not the pebbles and rock fragments. This selective result is effected by an arrangement which allows the surface of the chute at any lateral portion immediately below the roller, to yield or give way at an adjustable and predetermined pressure, which is set at such a value as to break the shell fragments but not

the pebbles and rock, the latter being passed on entire along the chute. The roller operates under an adjustable spring control and the yielding base of the chute immediately below it consists of a number of flat bars placed together edge uppermost pivotal or hinging near their intake end on an axis rightangular to the direction of the chute and supported near their other end by a cushion of rubber or other suitably resilient material or equivalent device. Thus all the material delivered into the chute passes the roller and is then subjected to a further selective process by which the lime ingredient passes freely along the chute to the delivery receptacle, whilst the pebbles and rocks are deflected into a side aperture of the chute and disposed of as refuse. This is effected by an oscillating baffle plate positioned transversely of the chute at a suitable distance below the roller, and presenting an angular surface to all the descending material, the lower edge of the baffle is cut away at suitable intervals leaving a narrow aperture adjacent the chute surface and of just sufficient height to allow the shell fragments only to pass, the pebbles being deflected angularly towards the sides of the chute and discharged through an opening therein.

To obviate the possibility of the material packing and piling up against the surface of the baffle, the latter is provided with a simple oscillating mechanism comprising an eccentric positioned behind the baffle and within the angular space formed by the intersecting sides, the eccentric is preferably driven from a transverse shaft carried over the sides of the chute and making connection with the sheave of the eccentric by a depending spindle and bevel gearing, the speed of this device is so adjusted that the progress of the material down the chute is maintained in a continuous, even, and rapid flow.

The invention is more clearly explained by the aid of the drawings herewith forming a part of this application in which

Fig. 1 is a side elevation of the device with the driving pulley removed.

Fig. 2 is a plan view.

Fig. 3 is an enlarged view of the roller and

adjacent parts showing the yielding surface of the chute below the roller, being a cross section through the centre of the bearing, and a further cross section in another parallel plane through the bottom of the chute showing the details of the yielding surface of the latter below the crushing roll.

Fig. 4 is a plan of the apex of the baffle member showing the position of the oscillating eccentric.

In these drawings the numeral 5 indicates the sides of the wooden chute, 6 the bottom or effective member, this is secured in connection with suitable framework and inclined at an angle of about 30 degrees depending upon the character of the material to be dealt with. The main driving pulley 7 revolves the roller 8 which is preferably fluted circumferentially so that the shell fragments are broken rather than pulverized. The chute surface immediately below the roller is so constructed as to give way at any point laterally under a predetermined pressure, and constitutes a salient feature of the invention. To effect this the surface of the chute at 9 is formed by a series of flat steel bars placed side by side each bar 10 being hinged on the transverse pin 11 and resting below the roller on a rubber cushion 12 supported by a bearer 13.

Thus when the adjusted pressure suited to fracture the clam shells is exceeded as a pebble is drawn under the roller the bar or bars immediately below it give way by compressing the cushion 12, thereby allowing the pebble to pass along the chute escaping at the space 14 when the cushion at once restores the bar 10 to its original level flush with the wood surface 6, the yielding pivotal bar is shown depressed at 15. The roller is carried by a bearing 16 at each side and fitted with means for regulating the pressure exerted by the spring 17. These may be of any usual form and call for no special comment. The angular and curved baffle 18 is located at a suitable distance beyond the roller 8, this consists of a flat plate normal to the surface of the chute and presenting a pair of curved sloping surfaces to all the descending material discharged from the roller 8. The lower edge of the baffle 18 does not rest upon the surface of the chute except intermittently at points of support, but is distanced therefrom by a narrow aperture sufficient in width to pass the shell fragments but not pebbles or rocks, this aperture is indicated at 19. An eccentric 20 carried by the vertical spindle 21 and actuated by the bevel gear 22 driven by the cross shaft 23 provides a suitable oscillating motion to the baffle 18 which is hinged on both sides at 24 to obtain a satisfactory and easy motion. The oscillating motion of the baffle 18 greatly facilitates the effective operation and rapidity of the process by preventing pos-

sible accumulation of the material on the upper side of the baffle plate, and is further effective by deflecting rock fragments and pebbles sideways of the chute whereby they are evacuated through the aperture 25 in 70 the sides of the chute.

Having now fully ascertained the nature of my said invention, what I claim as mine and desire to secure by Letters Patent, is:

In a combined crushing and separating machine having a trough shaped chute in which a transverse circumferentially fluted roller revolves the combination comprising, a yieldable base in that portion of the chute below and opposite the said roller whereby a specially hard substance may depress one portion of the chute base without depressing adjacent portions, a resilient member supporting the yieldable portion of said base, an oscillating baffle plate positioned across the base of said chute and having the form of two converging curved plates each with a double hinge adjacent the side of the said chute whereby the crushed material emerging from the roller may pass below the bottom edge of the baffle and the larger portions may be deflected to an exit by the curvature of the said baffle plates.
